UNITED STATES PATENT OFFICE.

MAY DIKE, OF BOSTON, MASSACHUSETTS.

DESIGN FOR A PAPER-WEIGHT.

SPECIFICATION forming part of Design No. 24,662, dated September 10, 1895.

Application filed September 13, 1894. Serial No. 522,944. Term of patent 3½ years.

To all whom it may concern:

Be it known that I, MAY DIKE, a citizen of the United States of America, and a resident of the city of Boston, in the county of Suffolk and State of Massachusetts, have invented a certain new and useful Design for a Paper-Weight, of which the following is a full, clear, and exact description.

This design consists of a base A in superimposed layers held together, and suitable for a wiper of pens, a doll's or other such like representation B of a person's head, which is mounted on said base A and makes the paper-weight, and a head covering or cap C on said doll's head, and the socket or rack D of said cap capable to receive and retain a penholder E.

The base A, doll's head B, and cap C are decorated or ornamented.

Having thus described my invention, what I claim, and desire to secure by Letters Patent, is—

The design for a paper weight, herein described and shown.

In testimony whereof I have hereunto set my hand in the presence of two subscribing witnesses.

MAY DIKE.
